[57] CLAIM

The ornamental design for a lounge chair, as shown and described.

DESCRIPTION

FIG. 1 is a perspective view of a lounge chair showing my new design;

FIG. 2 is a top plan view;

FIG. 3 is a front elevational view;

FIG. 4 is a rear elevational view;

FIG. 5 is a left side elevational view, the right side being a mirror image thereof; and,

FIG. 6 is a left side elevational view thereof showing the headrest in an alternate position.

FIG. 1 has been drawn to an enlarged scale with respect to FIGS. 2 through 6.
